COMBINATION IRONING BOARD, CHAIR,
AND LADDER UNIT

Arthur Edward Hinch, Toronto, Ontario, Canada

Application April 24, 1952, Serial No. 284,071

Claims priority, application Canada
April 27, 1951

7 Claims. (Cl. 155—42)

1

This invention relates to collapsible ironing boards, and in particular to an ironing board arranged in combination with an adjustable stand to provide a unit which is convertible into a chair or into a step ladder.

The object of the invention is to provide a combined ironing board and stand which is adapted to be adjusted manually to convert the combination into a chair or a portable step ladder without using tools and without altering the fixed relationship between any of the parts, by simply tilting the ironing board, forwardly or rearwardly as the case may be, into a substantially vertical position from a horizontal position.

A further object of the invention is to provide a combination as aforesaid in which the height of the ironing board above the floor is variable within a useful range without special adjustment.

In the accompanying drawings in which each reference character denotes the same part in all the views;

Fig. 1 is a perspective view of the normal arrangement of the ironing board and stand for use as such;

Fig. 2 is a side elevational view of the invention converted into a chair; and

Fig. 3 is a side elevational view of the invention converted into a ladder.

The ironing board 10, made either from wood, metal or other suitable material, is mounted on a metal frame providing a stand and comprising a front section A and a rear section B, the two sections being suitably hinged together, whereby the ironing board 10 and the rear section B of the frame may be tilted backwardly (toward the wide end of the board 10, see Fig. 2) into compact relation with the front section A of the frame to convert the combination into a chair, or tilted forwardly (toward the narrow end of the board and toward the front of the chair, see Fig. 3) to convert it into a step ladder.

The front section A comprises two identical side frame members 11, 11 formed into the shape of the front legs 11^a, rear legs 11^b and front seat-supporting portion 11^c of a chair. The rear legs 11^b have a stepped shape providing tread-supporting portions 11^d to accommodate a tread 12; this constitutes the first step of the ladder when the rear section B of the stand is tilted forwardly to the "ladder position" (see Fig. 3). Extensions of the frame members 11 are extended upwardly from the top of the front legs 11^a and are curved toward the rear to provide arms 13 and are then curved downwardly and forwardly to

2

provide a semi-circular portion 13^a meeting the rear legs 11^b.

The side frame members 11 may be secured together and braced by cross bars 14, 14 under the front seat-supporting portions 11^c, by the tread 12 extending between the stepped bends in the rear legs 11^b, and also by a front seat section 15 secured between the seat supports 11^c.

A drawer may be mounted under the seat 15 on the cross bars 14, 14 but in the illustrated embodiment of the invention, this space is adapted for use for storage by providing a floor 17^a and end and front panels 17^b and 17^c respectively. (This space is particularly useful for holding an iron and other articles used when ironing).

The rear section B of the stand comprises two identical side frame members 18, 18 formed into a stepped shape providing upper tread-supporting portions 18^a and lower tread-supporting portions 18^b to accommodate two further treads 19 and 20 respectively, extending between the two frame members; in the ladder position of Fig. 3 the frame members 18 above and below the lower tread-supporting portions 18^b provide upper and lower normally vertical portions 18^c and 18^d respectively and below the portion 18^d they extend rearwardly to provide horizontal rear seat-supporting portions 18^e between which is secured a rear seat section 15' to cooperate with the front seat section 15 and provide a seat of convenient size when the device is in the "chair position". In line with the junctions of portions 18^d and 18^e the rear section B is pivoted to the front section A by the hinges 15^a between the rear seat section 15' and the front seat section 15. The hinges 15^a are disposed at the exact center of the semi-circular portions 13^a and portions 18^b and 18^d are so dimensioned that the junction between them always lies exactly on the semi-circular curve of the said portions 13^a to permit the rear section B to be locked conveniently in any angular position. A locking device such as the device 21 adapted to be screwed against the said semi-circular portion is provided, including a bolt adjustably threaded in a lug on the portion 18^d, or another suitable fastening device may be disposed as required for the same purpose.

The ironing board 10 is swingably attached to the frame through links 22, 22, which are pivoted at one end to the bracket 23 at the mid-point of the ironing board and at the other end to the rear ends of the arms 13 on the front section A of the frame, directly above the hinge 15^a.

Extending outwardly from the upper tread-

supporting portions 18^a at the ends of the frame members 18 are end-threaded guide pins 24, and angle-members 25 at each side of the rear part of the ironing board 10 provide longitudinal depending flanges 26 having slots 26^a in which the guide pins 24 are received. The guide pins 24 slide from one end to the other of the slots 26^a when the ironing board is being pivotally adjusted into a rearward vertical relation to convert the combination into a chair, or into a forward vertical relation to convert the combination into a step ladder. On the threaded ends of the guide pins may be provided wing nuts 24^a to permit the guide pins to be fixed at any point along the slot 26^a. The fastening device 21 with the arrangement of threaded pins 24 and wing nuts 24^a allows the ironing board to be fixed in any horizontal position within a considerable range of height of the board from the floor. The position shown in the drawings is the position of maximum height in which the links 22, 22 are vertically disposed.

What I claim as my invention is:

1. A device of the character described comprising an ironing board and a stand adapted to support the ironing board at a convenient height above the floor, the stand comprising a front section in the form of a chair and providing a chair seat, and a rear section providing a step ladder, the front and rear sections being hinged together, one of the sections being shiftably connected to the ironing board and the other being pivotally and slidably connected to the ironing board so that the ironing board and the rear section may be tilted either forwardly or rearwardly to convert the board and the stand either into a step ladder or into a chair.

2. A device of the character described comprising an ironing board and a stand adapted to support the ironing board at a convenient height above the floor, the stand comprising a front section in the form of a chair and providing a chair seat and also providing a ladder step, and a rear section having the form of a ladder, the front section being pivotally connected to the rear section and shiftably connected to the ironing board and the rear section being pivotally and slidably connected to the ironing board so that the ironing board and the rear section may be tilted either forwardly or rearwardly from a horizontal into a substantially vertical position of the ironing board to convert the said device into a ladder or into a chair.

3. A device of the character described comprising an ironing board and a stand adapted to support the ironing board at a convenient height above the floor, the stand comprising a front section including spaced-apart end frames and having a seat and a step extending between the frames, a pair of links attached to the ironing board at one end and pivotally attached to the front section at the other, and a rear section including spaced-apart end frames and a step extending between the frames, the rear section being pivotally connected to the front section at a location spaced from the said pivotal connection of the ends of the links and being pivotally attached by longitudinally slidable engagement with the ironing board, whereby the ironing board is adapted to be supported in a horizontal position and is adapted to be tilted with the rear section either forwardly or rearwardly to a substantially vertical position of the ironing board, the rear section when the ironing board is tilted forwardly resting on

top of the front section whereby the step of the rear section is spaced from the step of the front section to provide a step ladder.

4. A device of the character described comprising an ironing board and a stand adapted to support the ironing board at a convenient height above the floor, the stand comprising a front section including spaced-apart end frames and having a seat section and a step extending between the frames, a pair of links attached to the ironing board at one end and pivotally attached to the front section at the other, and a rear section including spaced-apart end frames, a second seat section and a step extending between the frames, the rear section being pivotally connected to the front section at a location spaced from the said pivotal connection of the ends of the links and being pivotally attached by longitudinally slidable engagement with the ironing board, whereby the ironing board is adapted to be supported in a horizontal position and is adapted to be tilted with the rear section either forwardly or rearwardly to a substantially vertical position of the ironing board, the rear section when the ironing board is tilted forwardly resting on top of the front section whereby the step of the rear section is spaced from the step of the front section to provide a step ladder, the seat sections co-operating when the ironing board is tilted rearwardly to provide a seat in front of the ironing board.

5. A device of the character described comprising an ironing board and a stand adapted to support the ironing board at a convenient height above the floor, the stand comprising a front section including spaced-apart end frames and having a seat extending between the frames, the frames including a step extending between and supported above the floor by the frames at the rear of the seat, a pair of links attached to the ironing board and each pivotally connected to the front section, and a rear section including spaced-apart end frames and a step extending between the said frames, the rear section being pivotally connected to the front section at a location spaced from the said pivotal connection of the links and being pivotally attached by longitudinal slidable engagement with the ironing board, whereby the ironing board is adapted to be supported in a horizontal position and is adapted to be tilted with the rear section either forwardly or rearwardly to a substantially vertical position of the ironing board, the rear section when the ironing board is tilted forwardly resting on top of the front section whereby the step of the rear section is spaced from the step of the front section to provide a step ladder.

6. A device of the character described comprising an ironing board and a stand adapted to support the ironing board at a convenient height above the floor, the stand comprising a front section in the form of a chair and providing a chair seat and also providing a ladder step at the rear of the seat, and a rear section having the form of a ladder and providing a step spaced from the ends of the ladder, one end of the ladder being pivotally connected to the front section and the other end of the ladder being pivotally and slidably connected to the ironing board, the stand also including links connecting the ironing board pivotally to the chair at a point spaced from the connection of the ladder to the chair and spacing the ironing board from the chair, the ironing board and the ladder being tiltable either forwardly or rearwardly from

a horizontal into a substantially vertical position of the ironing board to place the latter respectively above the chair to convert the stand into a ladder or behind the chair to permit the chair to be used as such.

7. A device of the character described comprising an ironing board and a stand adapted to support the ironing board at a convenient range of heights above the floor, the stand comprising a front section in the form of a chair and providing a chair seat, and a rear section providing a ladder step, one end of the rear section being pivotally connected to the front section and the other end of the rear section being pivotally and slidably adjustably connected to the ironing board, the stand also including links pivotally connected to the ironing board and pivotally connected to the chair at a point spaced from the

connection of the rear section to the chair, the links being adapted to space the ironing board from the chair, the ironing board and the ladder being tilttable either forwardly or rearwardly from one of a range of horizontal positions into a substantially vertical position of the ironing board to place the rear section respectively above the chair to convert the stand into a ladder or the ironing board behind the chair to permit the chair to be used as such.
